UNITED STATES PATENT OFFICE.

NIKOLAI HILL, OF IRON BELT, WISCONSIN.

MOP HOLDER.

Application filed May 17, 1926. Serial No. 109,632.

This invention relates to new and useful improvements in mops, and particularly to holders therefor.

One object of the invention is to provide a mop holder which can be easily and quickly opened and closed, to permit the introduction of the fabric or cloth of the mop, to obviate the usual practice of threading an end of a length of cloth between the jaws of the 10 mop holder, and then pulling the same therethrough, before closing the jaws thereon.

Another object is to provide a mop holder which is simple in construction, and which can be easily operated without the use of any 15 special tools.

Another object is to provide a novel form of cloth clamping means, and means for holding the clamping means in cloth clamping position, as well as the same against accidental release.

Other objects and advantages will be apparent from the following description when taken in connection with the accompanying drawing.

25 In the drawing:

Figure 1 is an elevation of a mop holder made in accordance with one form of the present invention, the clamping means being in operative, or clamping position.

30 Figure 2 is an elevation of the device, showing the clamping means open to receive the cloth of the mop.

Figure 3 is a plan view of the same.

Figure 4 is a sectional view on the line 35 4-4 of Figure 3.

Figure 5 is an elevation of a modified form of clamping means.

Figure 6 is an elevation of a further modified form of the invention.

40 Referring to the accompanying drawing, and particularly to Figures 1 to 4, inclusive, 10 represents a portion of the stick, or handle of the mop holder, and secured to one end of said stick, in partially embracing relation thereto, is the shank portion 11, of one half of the inner jaw 12, of the mop head. The angularly extending portion 13, of the member 11 projects laterally from the end of the stick of the mop, and is terminally 45 bifurcated, as shown at 14, to receive therethrough one end of the outer clamping jaw 15. This end of the jaw 15, which is disposed between the furcations of the member 13 is rebent, at 16, and receives therethrough 50 the pivot member 17, which is also passed through said furcations. The other end of

the jaw 15 is similarly curved or rebent, at 18, and pivotally mounted in the bifurcated end of the other member 19, of the inner jaw. This member 19 is also provided with 60 a semi-tubular shank 20, which embraces the remaining portion of the end of the stick of the mop, and is provided with an opening 21, which receives the adjacent end of the bolt 22, which secures the first-named half 65 to the stick. Slidable on the stick, and arranged to enclose the shanks 11 and 20 whereby to maintain the latter shank in contact with the stick, and to cause its outer portion to cooperate with the corresponding portion of the other member 11, to maintain a 70 mop cloth tightly gripped between such portions and the jaw bar 15, is a sleeve 23.

When it is desired to place a cloth in the holder, the operator slides the sleeve 23 75 backwardly onto the stick, whereby to release the shank 20. The operator then swings the shank away from the stick, so that the parts assume the position shown in Figure 2, after which he drapes a cloth 80 across the jaw 15, with the intermediate portion of the cloth engaged with said bar. The parts are then swung back into the position of Figure 1, and the sleeve slipped into embracing engagement with the shanks. 85 The intermediate portion of the cloth is thus firmly clamped between the transverse portions of the shank members and the jaw 15.

In the form shown in Figure 5 the shanked members 24 have integral pivot 90 members 25 in their outer ends, with which are engaged the hooked ends of the jaw 15'. A leaf spring member 26 extends longitudinally of the jaw 15', and has its ends bifurcated, and disposed in straddling relation to 95 the end portions of said jaw 15'. The remainder of the device is as previously described with respect to the first form. The mop cloth is firmly gripped between the spring 26, which, as clearly seen in Figure 100 5, is bowed toward the members 24, and the said members.

In the form shown in Figure 6, the outer ends of the members 24' receive slidably therethrough the arms of the yoke 27, the 105 transverse portion of which corresponds to the clamping jaw 15, of the first form. On the upper ends of the members 24' there are formed teeth 28, which cooperate with the said transverse portion of the yoke, to clamp 110 the intermediate portion of a mop cloth therebetween. On the said arms of the yoke,

inwardly of the members 24', are coil springs which urge the yoke in the direction of the members.

What is claimed is:

- 5 1. A mop holder including a stick, a clamping jaw formed of two sections, each section having a complementary shank receiving the stick end, one of the shanks being permanently secured to the stick and 10 the other releasably engageable therewith, a second clamping jaw pivotally connected at each end to the sections forming said first jaw, and means slidable on the stick into and out of embracing relation to the said 15 shanks for holding the parts in mop cloth clamping position.
2. A mop holder including a stick, a T-shaped jaw formed of two sections, each section having a complementary shank which receives an end of the stick therein, one of the shanks being fixedly secured to the stick, and the other detachably engaging the stick 20

a second jaw pivotally connected at its ends to the outer ends of said first jaw, and a resilient mop engaging face on said second 25 jaw.

3. A mop holder including a stick, a clamping jaw formed of two sections, each section having a complementary shank receiving the stick end and a laterally directed 30 portion forming a part of said jaw, one of the shanks being fixedly secured to the stick end and the other releasably engageable therewith, a second clamping jaw having angularly extending ends movably connected with the outer ends of the laterally directed portions, and a spring member disposed between the first and second jaws and having its ends embracing said angularly 35 extending ends.

In testimony whereof, I affix my signature.

NIKOLAI HILL.
